AUGUST V. BAYER, OF ST. LOUIS, MISSOURI, ASSIGNOR TO BAYER STEAM SOOT BLOWER COMPANY, OF ST. LOUIS, MISSOURI, A CORPORATION OF MISSOURI.

BOILER-CLEANER.

1,026,141.

Specification of Letters Patent. Patented May 14, 1912.

Application filed December 1, 1911. Serial No. 663,350.

To all whom it may concern:

Be it known that I, AUGUST V. BAYER, citizen of the United States, residing at St. Louis, State of Missouri, have invented certain new and useful Improvements in Boiler-Cleaners, of which the following is a full, clear, and exact description, reference being had to the accompanying drawings, forming a part hereof.

10. My invention has relation to improvements in boiler-cleaners; and it consists in the novel details of construction more fully set forth in the specification and pointed out in the claims.

15. In the drawings, Figure 1 is a side elevation of a portion of a water-tube boiler (with parts in section) showing my invention applied thereto; Fig. 2 is a vertical cross-section of the furnace-wall on the line 2—2 of Fig. 1, the cleaner attachment or blower being in side elevation and partly broken; Fig. 3 is a horizontal section on the line 3—3 of Fig. 2; Fig. 4 is an enlarged vertical section on the line 4—4 of Fig. 2 showing a front view of the steam-joint identified with the cleaning nozzle; Fig. 5 is a rear elevation of the joint; Fig. 6 is a combined side view and longitudinal section on the line 6—6 of Fig. 5; Fig. 7 is a cross-section on the line 7—7 of Fig. 5 with the rocker-member of the joint turned to one of its extreme limits; Fig. 8 is a part longitudinal middle section and part side elevation of the rocker-member of the joint detached; Fig. 9 is a plan of the link connection between the rocker-bar and movable or rocker member of the joint; Fig. 10 is a combined elevation and section on the line 10—10 of Fig. 9; Fig. 11 is a sectional detail on the line 11—11 of 40 Fig. 8; and Fig. 12 is a side view of a conventional form of steam-joint for which the joint of the present invention is substituted.

45. The present invention is an improvement on the soot-blower or boiler-cleaner forming the subject-matter of an application filed by myself and Gideon P. Brown, Serial Number 656,743; and while having the same objects in view and contemplating the several 50 advantages of said pending application, the present improvement has for its object to interpose between the fluid-supply pipe, header or riser, and the oscillating cleaning nozzle, a hollow joint which shall afford to

the fluid a passage-way of a substantially 55 uniform cross-section irrespective of the angle to which the nozzle has been oscillated from its central position, in either direction.

A further object is to provide a joint 60 which will reduce the length of traverse of the fluid (steam) from the riser to the spray-head or discharge mouth of the nozzle; a joint which can be easily manipulated, readily attached, and easily cleaned.

65. The invention consists of further and other features the advantages of which will be readily apparent from a detailed description of the invention which is as follows:

70. Referring to the drawings, F represents the furnace (the walls being broken away) of a well known type of water-tube boiler, S the shell of the boiler, and T the water-tubes, the latter being disposed in superposed planes and in the present illustration being inclined to the horizontal. Only a portion of the boiler is here illustrated, said portion being that immediately over the fire-box F' and in front of the bridge-wall B. Disposed along one of the side walls of the furnace opposite the tubes T is an opening O on the order of that of the pending application aforesaid, a transversely slotted plate P being set in the brick work across the opening at a point between the opposite 75 faces of the wall as well understood in the art, the slots s (elliptical in the present illustration) being availed of for the passage therethrough of the oscillating cleaning nozzles as presently to be seen. The top and bottom of the outer portions of the opening O are provided with a shoe or casting 1 between which is rigidly mounted a vertical steam pipe, riser or header 2, the riser being 80 tapped at the bottom by a steam-supply pipe 3 receiving its steam from any suitable 85 source but preferably from the steam space of the shell S (the connection not being shown as it is well understood in the art).

90. Distributed along the wall of the riser 2 100 opposite the spaces between the tubes T (and beyond the outer tubes if desirable), are short pipes 4 projecting toward the plate P, the riser 2 being opposite the longitudinal center or axis of the opening O. 105 The ends of the pipes 4 adjacent the plate P are screwed to the nipple n of the stationary section, member or casing 5 of a steam joint,

the nipple n terminating in a polygonal head h whereby it may be seized by a wrench and screwed to the pipe 4. Diametrically opposite the passage-way of the nipple n , 5 the casing wall is provided with a laterally elongated mouth or outlet opening bounded by a rim or flange 6, the side walls of which taper inwardly (see Fig. 7) and at an angle which determines the limit to which the 10 nozzle shall be oscillated from a central position, the nozzle being arrested when it strikes said inclined side wall of said mouth. The member 5 is more or less tapering in form being open at the top and bottom, 15 forming a casing for the reception of the rotatable or rocker-member 5', the bottom of which is provided with a D-shaped stud 6' from the face of which projects a screw-stem 7 as shown. The stud 6' is designed to 20 enter a corresponding opening in a washer 8, the latter being held in position by a nut 9 passed over the stem 7, the two sections or members 5, 5', being thus held together. The upper face of the member 5' is provided 25 with a hollow boss 10 positioned to one side of the axis of the member, the axis of the socket of the boss being at right angles to the axis of the member (5') and the socket being interiorly screw-threaded for the purpose of coupling the same thereto to a short 30 lever arm 11 as shown. The outer end of the lever 11 terminates at a point between the member 5' and the riser 2, and to it is screwed a ball 12 (Fig. 9) which is received 35 by a socket 13 at one end of the sectional link 14, the opposite end of the link terminating in a corresponding socket 15 the ball 16 of which has secured to it an arm or lever 17, a series of such arms being distributed 40 along a vertical rock-shaft or rocker-bar 18 mounted rotatably between the shoes 1, 1, and to one side of the riser 2. The bar 18 is provided with a handle-lever 19 by which it may be manipulated. By seizing the handle 45 and rocking the bar 18, it is obvious that from the connections described, a simultaneous rotation may be imparted to all the members 5' of the series.

The member 5' is provided with a transverse passage-way a terminating at one end in a screw-threaded cylindrical enlargement b (Fig. 8) with which it forms a shoulder 20, and at the opposite end in a dish-shaped enlargement or basin c the walls of the latter being more or less concaved and forming 55 a sort of pocket for directing the steam without friction or material interruption into the passage a and into the nozzle 21 which is screwed into the enlargement b 60 against the arresting shoulder 20. The nozzles pass freely through the slots s of the plate P and terminate on the inside of the furnace opposite the spaces between the tubes in spray-heads 22.

65 The sides of the openings in the sockets

13, 15, through which the members 11 and 17 respectively project are of course properly and sufficiently recessed to allow these members and the link 14 to assume the necessary angular relation brought about by the rocking of the bar 18. The present form of steam-joint (5, 5') permits such joint to be brought squarely up to the plate P , thus bringing the axes of oscillation of the nozzles 21 (these axes corresponding to the axes of rotation of the members 5') close to the slots s and making it possible to impart a maximum angular sweep or oscillation to the nozzles 21 with a minimum sweep of the lever 19 (Fig. 3). 70

The advantages of the present construction will appear from a description of the operation of the invention which is as follows:—The central position of the nozzles 21 is that indicated in Fig. 3, where the nozzle 80 passes through the slot s at right angles to the plane of the plate P . By oscillating the lever handle 19 to the right or left and rocking the bar 18, the nozzles will be correspondingly oscillated, and the steam being 90 previously turned into the pipe 3, the same will flow from the riser 2 into the several nozzles and be projected out of the terminal spray-heads 22 into, through, and across the spaces between the tubes, the axes of the rotatable joint sections 5' being set at right angles to the tubes T (Fig. 4) so that the several nozzles may sweep in planes substantially parallel to the boiler tubes. The maximum angle of oscillation of a nozzle 95 from its central position is reached when the nozzle strikes or engages the inclined side portions of the rim 6 bounding the opening in the casing 5 through which the nozzle plays (Fig. 7); and it will be observed by examining said figure (7) that whatever be the angle to which the nozzle 100 21 is oscillated, the position of the enlargement c of the passage a of the rocker-member 5' is such as to direct the steam from the 105 pipe 4 and intake nipple n into the nozzle 21 in practically a direct line from the riser 2 to the nozzle, the steam having no sharp angles or turns to encounter, and suffering no constriction whatever along the line, the 110 passage-way accorded thereto being substantially uniform in cross-section at all points between the riser 2 and the spray-head 22. It is thus seen that the steam is free to flow from the riser into and out of 115 the nozzle with the full boiler pressure behind it, suffering no loss from corners or constrictions. By the old method the steam flowed from a stationary steam-joint section such as R (Fig. 12) around a corner into 120 the rotatable section R' , and thereby lost much of its effectiveness by the time it reached the nozzle. During the rocking of the member 5', the washer 8 (which is 125 locked to the boss 6') of course rocks with 130

said member, the nut forcing the washer into firm contact with the end of the casing 5 so as to make a practically tight joint.

Having described my invention, what I 5 claim is:—

1. In combination with a fluid-conducting pipe, a stationary hollow joint section connected thereto and communicating therewith, a rotatable section mounted in the stationary section and provided with a passage-way opposite to, and in direct continuation of, the inlet to the stationary section, said passage-way terminating in an enlargement on the side facing the inlet to the stationary 15 section, said enlargement being in permanent communication with said inlet.

2. In combination with a fluid-conducting pipe, a stationary hollow joint section connected thereto and communicating therewith, a rotatable section mounted in the stationary section and provided with a transverse passage-way opposite to, and in direct continuation of, the inlet to the stationary section, said passage-way terminating in an 25 enlargement on the side facing the inlet to the stationary section, said enlargement being in permanent communication with said inlet, and a nozzle leading from said transverse passage-way of the rotatable section through the wall of the stationary section.

3. In combination with a fluid-conducting pipe, a stationary hollow joint section connected thereto and communicating therewith, a rotatable section mounted in the stationary section and provided with a transverse passage-way opposite to, and in direct continuation of, the inlet to the stationary section, said passage-way terminating in a 35 basin or dish-shaped enlargement on the side facing the inlet to the stationary section, said basin being in permanent communication with said inlet, and a nozzle leading from said transverse passage-way of the rotatable section through the wall of the stationary section.

4. In an apparatus of the character described, a joint comprising an outer hollow section or casing provided with a peripheral intake and an outlet opening opposite thereto, a rotatable member in said casing provided with a transverse passage-way between said intake and outlet opening, said transverse passage-way terminating in an 45 enlarged basin on the intake side of the casing in full and permanent communication with the said intake, a nozzle leading from the discharge end of said transverse passage-way and operating through the outlet opening of the casing, the bounding walls of said outlet opening arresting the rotation of the rotatable member by engaging the nozzle when the latter has been oscillated to one of its extreme positions.

5. In an apparatus of the character de-

scribed, a joint comprising an outer hollow casing provided with a peripheral intake and a laterally enlarged outlet opening opposite said intake, a rim bounding said outlet, the sides of the rim converging inwardly, an inner rocker member provided with a transverse passage-way between the intake and outlet of the casing, said transverse passage terminating on the side of the intake in a basin-shaped enlargement, and 50 at the opposite end in a cylindrical enlargement separated by a shoulder from the passage-way, a nozzle inserted in said cylindrical enlargement and limited by said shoulder, the converging portions of the rim 55 of the outlet opening of the casing being positioned to arrest the nozzle and thus maintain the basin in full and permanent communication with the intake opening of the casing.

6. In combination with a fluid-conducting pipe or header, an oscillating nozzle, and a hollow-joint interposed between said nozzle and header and provided with passage-ways opposite the nozzle according a 60 flow to the stream from the header across the joint in a substantially direct line to the nozzle.

7. In an apparatus of the character described, a joint comprising an outer hollow section or casing provided with a peripheral intake, and an outlet opening opposite thereto, a rotatable member in said casing provided with a transverse passage-way between said intake and outlet opening, said 65 transverse passage-way terminating in an enlarged basin on the intake side of the casing in full and permanent communication with said intake, and a nozzle leading from the discharge end of said transverse 70 passage-way and operating through the outlet opening of the casing.

8. In an apparatus of the character described, a joint comprising a casing having a peripheral intake, and an outlet opening opposite thereto, an inner rocker member rotatable about an axis disposed at an angle to the common axis of the intake and outlet openings of the casing, said rocker member being provided with a transverse passage the 75 axis of which is disposed in the plane of the common axis of the intake and outlet openings of the casing, said passage terminating in an enlargement in permanent communication with the intake to the casing, and discharging through the outlet from the casing.

9. In an apparatus of the character described, a joint comprising a casing having a peripheral intake, and an outlet opening opposite thereto, an inner rocker member rotatable about an axis disposed at right angles to the common axis of the intake and outlet openings of the casing, said rocker member being provided with a transverse 80

passage the axis of which is disposed in the plane of the common axis of the intake and outlet openings of the casing, said passage terminating in an enlargement in permanent communication with the intake to the casing, and discharging through the outlet from the casing.

In testimony whereof I affix my signature, in presence of two witnesses.

AUGUST V. BAYER.
